UNITED STATES PATENT OFFICE.

BENJAMIN F. MEYER, OF CAMDEN, NEW JERSEY, ASSIGNOR TO M. A. FUR-BUSH & SON MACHINE COMPANY, OF SAME PLACE.

AUTOMATIC STOP AND RELEASING DEVICE FOR LOOMS.

SPECIFICATION forming part of Letters Patent No. 672,385, dated April 16, 1901.

Application filed November 27, 1900. Serial No. 37,866. (No model.)

To all whom it may concern:

Be it known that I, BENJAMIN F. MEYER, a citizen of the United States, residing at Camden, in the county of Camden and State of New Jersey, have invented certain new and useful Improvements in Automatic Stop and Releasing Devices for Looms, of which the following is a specification.

My invention has relation to a mechanism for automatically stopping a loom by releasing the operating-shaft from the main driving-gear when the shuttle fails to reach its box; and in such connection it relates to the construction and arrangement of such a mechanism.

The nature and scope of my invention will be more fully understood from the following description, taken in connection with the accompanying drawings, forming part hereof, in which—

Figure 1 is an end elevational view of a power-loom, illustrating the power end and the automatic stop and releasing device embodying main features of my invention applied thereto. Fig. 2 is a top or plan view of Fig. 1. Fig. 3 is a detail view of the gear on the operating-shaft of the loom and of the means for connecting the same to said shaft. Fig. 4 is a front elevational view, enlarged, of the shuttle-box and protector-finger. Fig. 5 is a top or plan view of Fig. 4, with a portion of the frame of the loom broken away to illustrate the construction and arrangement of the stop and releasing device. Fig. 6 is a cross-sectional view on the line 6-6 of Fig. 4, and Fig. 7 is a detail view of the shipper-catch.

Referring to the drawings, *a* represents the main driving-pulley, operated by a belt *a'* from a power-shaft. (Not shown.) The pulley *a* normally rotates loosely upon the driving-shaft *b* of the loom adjacent to a friction-pulley *b'*, keyed to the shaft *b*. The pulley *a* has a face *a²*, adapted when the pulley is shifted on the shaft *b*, as hereinafter described, to engage the pulley *b'* and to transmit its power and motion thereto. The driving-shaft *b* has a bevel-pinion *b²*, engaging a main driving-gear *b³*, which in turn is adapted to mesh with a gear-wheel *b⁴*, controlling the operating-shaft *d* of the loom. The pulley *a* is provided with a grooved collar *a⁴*, engaged by a forked

clutch *a⁴*, operated by a series of levers *a⁵*, *a⁶*, and *a⁷*. The lever *a⁷* is connected by a rod *a⁸* with a treadle *a⁹*, adapted to be depressed by the foot of the operator to throw the pulley *a* against the pulley *b'* through the connection heretofore set forth. The treadle *a⁹* is normally elevated by the spring *a¹⁰* and is also controlled in its movement by a handle or hand-lever *a¹¹*, connected by the rod *a¹²* with said treadle, all as clearly illustrated in Fig. 1.

So far as explained the mechanism is arranged and operates in a manner well known in the art. By depressing the treadle *a⁹* the loom is set in operation, and by either elevating the treadle or causing the handle *a¹¹* to shift the power-pulley *a* is disconnected from the pulley *b'* to stop the loom. The shuttle-boxes *e* and shuttle-lay *e'* are connected by a link *e²* with a crank *d'* of the operating-shaft *d*. If for any reason the movement of the lay *e'* is stopped—as, for instance, when the shuttle *e³* is not in its box and strikes upon the batten—then the connecting-link *e²* will be forced backward and the rotation of the shaft *d* will be reversed.

In the construction so far described the uncoupling of the pulley *a* from the pulley *b'* will not prevent further rotation of the main gear *b³*, which travels by reason of its momentum, and as the gear *b⁴* on the operating-shaft *d* will be reversed in movement by the reversal of the shaft *d* the teeth of the gear *b⁴* will be subjected to great strain and will break off under the pressure exerted by the moving main gear *b³*. To prevent this destruction of the gear *b⁴* is one of the main features of the present invention and is secured by the following mechanism: The gear *b⁴* is loosely supported upon the operating-shaft *d* and is provided on one face with a grooved collar *f* and on the other face with preferably two diametrically opposite lugs or projections *f'*. Adjacent to that face of the gear *b⁴* which carries the lugs *f'* is located a hand-wheel *f²*, keyed to the shaft *d* and provided with an annulus or ring *f³*, having openings or recesses adapted to receive the lugs *f'*, to thereby lock the gear *b⁴* to the ring *f³*, and hence to the hand-wheel *f²* and shaft *d*. The locking of the gear *b⁴* to the shaft *d* is only

accomplished when the gear b and its collar f are shifted in one direction on the shaft d , and the disengagement of the gear b^4 from the shaft d is secured by the shifting of the 5 gear b^4 and collar f in an opposite direction on said operating-shaft d . The shifting mechanism consists, preferably, of a forked clutch f^4 , engaging the collar and operated by a rod f^5 , which extends forward to the frame in front 10 of the shuttle-lay e' and is connected to a lever f^6 , called a "bumper-iron." This lever or bumper-iron f^6 is pivoted at one end, as at f^7 , and intermediate of the pivot f^7 and the connection to the rod f^5 is provided with 15 a projection f^8 . It follows that when the bumper-iron f^6 is moved outward away from the front of the lay e' then the rod f^5 is drawn out and through the clutch f^4 will draw the gear b^4 out of engagement with the hand-wheel 20 ring f^3 .

Referring now to Figs. 4, 5, and 6, in front of the shuttle-box e is arranged for each shuttle a plate e^4 , normally pressed inward by a spring e^{15} and designed to check or brake the 25 movement of the shuttle e^3 as it enters the box and to hold the shuttle in the box until the next pick. This plate e^4 has a free end e^5 , which when the shuttle e^3 occupies its box is pressed outward, as indicated by dotted lines 30 in Fig. 5. Adjacent to the free end e^5 of the plate e^4 is one arm g , secured to a shaft, which carries another arm g' , constituting what is called a "protector-finger." When the shuttle e^3 is not in its box, the protector-finger g' 35 is elevated by a spring g^2 to the position indicated in full lines in Fig. 6 and in this position is in alinement with and will strike against the projection f^8 of the bumper-iron f^6 . When the shuttle e^3 is in its box, the finger g' will be depressed by the bulging out of the free end of the plate e^4 , as indicated in dotted lines in Fig. 6, to clear the projection f^8 . It follows then that if the shuttle e^3 fails to enter its box as required the 40 protector-finger g' , as the box e swings toward the frame, will strike the bumper-iron f^6 and move it outward, and thereby, as hereinbefore explained, will cause the uncoupling of the gear b^4 from the hand-wheel ring f^3 , and the 45 gear b^4 will run idle upon the operating-shaft d . Hence whether or not the pulley a is uncoupled from the pulley b' the shaft d of the loom will instantly stop rotating and there can be no breakage of the teeth of the gear 50 b^4 , which continues to rotate in mesh with the main gear b^3 as long as said gear b^3 is driven and without operating the loom.

A second feature of my invention consists in connecting the bumper-iron f^6 , which serves 55 to uncouple the gear b^4 from the shaft d , with the clutch-operating mechanism for uncoupling the power-pulley a from the driving-pulley b' . The bumper-iron f^6 is normally pressed inward toward the protector-finger g' by 60 means of a catch m , known as a "shipper-

catch," which is under the tension of a spring m' . The catch m is pivoted, as at m^2 , in the loom-frame and carries a pin m^3 , normally resting against a piece f^9 , adjustably secured to the free end of the bumper-iron f^6 . 70 The catch m is also provided with a beveled lug m^4 , adapted when the catch moves under the tension of the spring m' to engage a finger a^{13} , secured to the handle a^{11} , and to hold said handle a^{11} in position. From the 75 description heretofore given of the handle a^{11} , rod a^{12} , treadle a^9 , and the spring a^{10} it will be understood that the handle a^{11} is normally held in elevated position by the spring a^{10} , which acts upon the treadle a^9 to elevate the 80 rod a^{12} . The catch m therefore, under the influence of its spring m' , serves to shift the bumper-iron f^6 into its normal position and to lock the handle a^{11} against the tension of the treadle-spring a^{10} , or, in other words, the 85 catch normally maintains the mechanism for uncoupling the gear b^4 in an inoperative position and also serves to lock the treadle a^9 in its depressed position, which position insures the coupling of the power-pulley a with 90 the driving-pulley b' . The movement of the bumper-iron f^6 when struck by the protector-finger g' retracts the catch m , so as to permit the lug m^4 to clear the finger a^{13} of the handle a^{11} , and thus permits the handle a^{11} to be elevated by the treadle a^9 under the influence of the treadle-spring a^{10} . 95

Having thus described the nature and objects of my invention, what I claim as new, and desire to secure by Letters Patent, is— 100

In a device of the character described, a main driving-shaft, a driving-pulley secured thereto, a power-pulley adapted to be locked to or released from the driving-pulley to control the movement of the driving-shaft, a 105 treadle mechanism adapted to lock or release said pulleys, a hand-lever adapted to control the treadle mechanism, a shipper-catch normally adapted to maintain the hand-lever in inoperative position, a bumper-iron or lever 110 controlling said catch, an operating-shaft, a lay adapted to be oscillated by said shaft, a shuttle-box carried by said lay, a gear normally locked to said shaft, a driving-gear carried by the main driving-shaft and in mesh 115 with the gear on the operating-shaft, means controlled by the bumper-iron for unlocking the gear to the operating-shaft, and a protector-finger normally elevated when the shuttle-box is empty and adapted to control 120 the bumper-iron, substantially as and for the purposes described.

In testimony whereof I have hereunto set my signature in the presence of two subscribing witnesses.

BENJAMIN F. MEYER.
